UNITED STATES PATENT OFFICE.

WILHELM WURL, OF WEISSENSEE, BERLIN, GERMANY.

DRYING APPARATUS.

1,411,199.

Specification of Letters Patent. Patented Mar. 28, 1922.

Application filed August 12, 1921. Serial No. 491,760.

(GRANTED UNDER THE PROVISIONS OF THE ACT OF MARCH 3, 1921, 41 STAT. L., 1313.)

To all whom it may concern:

Be it known that I, WILHELM WURL, a citizen of the German Republic, and a resident of Weissensee, Berlin, Germany, have invented a new and useful Drying Apparatus, of which the following is a full, clear, and exact description.

This invention relates to drying apparatus and has for an object to provide an improved construction for drying in an efficient manner granular material in a continuous operation.

Another object in view is to provide a drying apparatus in which the drying medium enters at one side and leaves at the opposite side while the material being dried is forced longitudinally of the apparatus and transversely of the movement of the drying medium.

20 A still further object of the invention is to provide a drying apparatus formed with stirring and conveying means which will divide the apparatus into chambers so that a drying medium may be independently discharged into the chamber and thereby present a fresh drying medium to the matter being dried as it moves from one end of the apparatus to the other.

In the accompanying drawings:

30 Figure 1 is a longitudinal vertical section through a drying apparatus embodying the invention, certain parts being shown in elevation.

Figure 2 is a transverse sectional view 35 through Figure 1 approximately on line 2—2.

Figure 3 is a top plan view of the apparatus shown in Figure 1, the hopper being removed.

40 Figure 4 is a perspective view of a pair of division plates and a plurality of conveying blades embodying certain features of the invention.

Referring to the accompanying drawings 45 by numerals 1 indicates a stationary tubular casing having an inlet opening at 2 and an outlet opening at 3. Casing 1 is closed at the ends in any desired manner, as for instance by the end walls 4 and 5, which if 50 desired may act as a support for the casing. A shaft 6 preferably hollow extends through the casing centrally and preferably through the side walls 4 and 5 so as to be properly journaled, one end of said shaft being provided with a pulley or other driving means 55 7. Rigidly secured to the shaft 6 is a plu-

rality of disks 8, each disk being provided with a pair of openings 9 and 10, and extending through the openings 9 and 10 is a conveying blade 11, which is formed with a pair of side members 12 and 13 and a bottom 14 curved at 15 so as to scrape against the casing 1 as indicated in Figure 2. The end 16 opposite 15 falls short of casing 1 so that the matter on the blade may freely fall 60 therefrom under the action of gravity. The blade 11 carried by the disk 8 gathers up the material 17, which is being dried, on one side of the disk 8 and discharges the same on the other side. The next disk is 70 provided with a similar blade which acts in a similar manner and so on for the full length of the apparatus.

The granular matter to be dried may be a sludge of any kind, or in fact any granular matter having moisture therein which is desired to be removed. The matter to be dried is fed in through the hopper 18 and as it is passed through the opening 2 it will be scraped up by the first set of blades 11, 80 there being preferably two blades to each disk 8, though this structure is not absolutely necessary. The two first blades pick up and then discharge the matter into the next chamber between the two first disks 8. 85 The blades in this chamber will pick up the matter and discharge it to the next chamber and so on until the dried material is discharged out opening 3.

In order to dry the material as it passes 90 through the apparatus a supply header 19 is provided, which supplies hot air, gases, or other drying mediums to comparatively small pipes 20 positioned in such a manner that there will be one pipe 20 for each of 95 the chambers or spaces between the disks 8 as indicated in Figure 3. A withdrawal pipe 21 is provided for each of the chambers or spaces between the disks 8, said withdrawal pipes being connected to a discharge header 22. It will be noted that by this arrangement the hot gas or other drying medium moves transversely across the casing 1 and by the time it becomes substantially saturated with moisture it has 105 reached the discharge pipe 21. It will also be noted that a continuous fresh supply of drying air is supplied to each chamber so that there will be an ample absorption by the air of the moisture in the last chamber 110 as well as the first, whereby the material is discharged in a highly dried state. As the

new supply of hot air is inserted into each chamber continuously the blades and the disks 8 become heated so that they will act in addition to stirring and transporting means as heaters for heating the material on its way to the discharge opening 3. If desired a valve 23 could be provided in header 19 for controlling the amount of drying medium used in order that just a sufficient quantity may be utilized to produce the desired drying action.

What I claim is:

- 15 1. A drying apparatus of the character described comprising a stationary casing, a plurality of revolving conveying members for conveying matter to be dried from one end of the casing to the other, and means for admitting a drying medium into said casing along one side at right angles to the conveying members, and means for removing the vapor laden drying medium from the opposite side of said casing.
- 20 2. A drying apparatus for sludges and the like comprising a stationary casing, stirring and conveying members arranged in the casing for stirring and conveying the sludge from one end of the casing to the other, and means for causing a drying medium to pass through the casing from one side to the other at right angles to the stirring and conveying members for removing the moisture from said sludge.
- 25 3. A drying apparatus of the character described comprising a stationary casing, a plurality of spaced disks arranged in the casing whereby chambers are provided in the casing, a conveying blade connected with each of said disks and extending from one side of the respective disks to the opposite side so as to convey matter from one side of the disk to the other, a rotating shaft rigidly secured to said blades and said disks for rotating the same, said casing being provided with an inlet near one end and an outlet at the opposite end, means for directing a drying medium into each of said chambers, and means for removing the drying medium and the moisture absorbed thereby from the diametrically opposite side of said casing.
- 30 4. A drying apparatus of the character

described comprising a stationary tubular casing, a tubular conveyer arranged in the casing positioned to convey the material to be dried from one end of the casing to the other, means for rotating said conveyer, a plurality of spaced hot air supply pipes arranged on one side of the casing adapted to discharge hot air into the casing, and a plurality of discharge pipes for withdrawing the moisture laden air from the casing, said discharge pipes being substantially diametrically opposite to the inlet pipes.

5. A drying cylinder of the character described comprising a cylindrical casing, and provided with an opening adjacent each end, one of said openings indicated as an inlet and the other as an outlet, a plurality of spaced rotating disks positioned in the casing, a shaft connected with said disks for rotating the same, each of said disks having a pair of oppositely positioned openings therein, a conveyer blade arranged in each of said openings formed with a discharge end and with a scraping end adapted to scrape against the casing as the disks rotate, said blades extending through said openings so as to scrape up material from said casing on one side of the respective disks and discharging the same on the opposite side, means for directing a drying medium between each of the respective disks, said means being arranged on one side of the casing, and means for discharging the moisture laden air from the opposite side of said casing, said means opening into the space between the respective disks.

6. A drying apparatus, comprising a casing, conveying means in the casing for conveying the material through the casing, and means for causing a drying medium to pass through the casing at different points in the length thereof and at right angles to the conveying means.

7. A drying apparatus, comprising a casing, conveying means in the casing for conveying the material therethrough, said means dividing the casing into a plurality of chambers, means for causing a drying medium to pass through each chamber at right angles to the conveying means.

WILHELM WURL.
